(57) **CLAIM**

The ornamental design for a flavor pouch, as shown and described.

DESCRIPTION

FIG. 1 is a top perspective view of a flavor pouch showing a first embodiment my new design.

FIG. 2 is a bottom perspective view thereof.

FIG. 3 is a front elevational view thereof, the rear elevational view being a mirror image thereof.

FIG. 4 is a side elevational view thereof, the opposite side elevational view being a mirror image thereof.

FIG. 5 is a top plan view thereof.

FIG. 6 is a bottom plan view thereof.

FIG. 7 is a top perspective view showing a second embodiment of my new design.

FIG. 8 is a bottom perspective view thereof.

FIG. 9 is a front elevational view thereof, the rear elevational view being a mirror image thereof.

FIG. 10 is a side elevational view thereof, the opposite side elevational view being a mirror image thereof.

FIG. 11 is a top plan view thereof.

FIG. 12 is a bottom plan view thereof.

FIG. 13 is a top perspective view showing a third embodiment of my new design.

FIG. 14 is a bottom perspective view thereof.

FIG. 15 is a front elevational view thereof.

FIG. 16 is a rear elevational view thereof.

FIG. 17 is a top plan view thereof.

FIG. 18 is a bottom plan view thereof; and,

FIG. 19 is a side elevational view thereof, the opposite side elevational view being a mirror image thereof.
